(57) **CLAIM**

The ornamental design for a toy car as shown and described.

DESCRIPTION

FIG. 1 is a perspective view of a toy car showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is the first partial enlarged view of area 9 taken from FIG. 1 thereof;

FIG. 10 is the second partial enlarged view of area 10 taken from FIG. 1 thereof;

FIG. 11 is the third partial enlarged view of area 11 taken from FIG. 1 thereof;

FIG. 12 is the fourth partial enlarged view of area 12 taken from FIG. 1 thereof; and,

FIG. 13 is the fifth partial enlarged view of area 13 taken from FIG. 2 thereof.

The dash-dot broken lines are included to annotate partial views in FIGS. 9-13. All other broken lines represent portions of the article that form no part of the claimed design. None of the broken lines form a part of the claim.
